(57) **CLAIM**

The ornamental design for a container with lid, as shown and described.

DESCRIPTION

FIG. 1 is a top perspective view of a first embodiment of a container with lid in a first position showing our new design;

FIG. 2 is a front view of the container and lid shown in FIG. 1;

FIG. 3 is a rear view of the container and lid shown in FIG. 1;

FIG. 4 is a left side view of the container and lid shown in FIG. 1;

FIG. 5 is a right side view of the container and lid shown in FIG. 1;

FIG. 6 is a top view of the container and lid shown in FIG. 1;

FIG. 7 is a bottom view of the container and lid shown in FIG. 1;

FIG. 8 is a top perspective view of the container with lid shown in FIG. 1 in a second position;

FIG. 9 is a front view of the container and lid shown in FIG. 8;

FIG. 10 is a rear view of the container and lid shown in FIG. 8;

FIG. 11 is a left side view of the container and lid shown in FIG. 8;

FIG. 12 is a right side view of the container and lid shown in FIG. 8;

FIG. 13 is a top view of the container and lid shown in FIG. 8;

FIG. 14 is a bottom view of the container and lid shown in FIG. 8;

FIG. 15 is a top perspective view of a second embodiment of a container with lid in a first position;

FIG. 16 is a front view of the container and lid shown in FIG. 15;

FIG. 17 is a rear view of the container and lid shown in FIG. 15;

FIG. 18 is a left side view of the container and lid shown in FIG. 15;

FIG. 19 is a right side view of the container and lid shown in FIG. 15;

FIG. 20 is a top view of the container and lid shown in FIG. 15;

FIG. 21 is a bottom view of the container and lid shown in FIG. 15;

FIG. 22 is a top perspective view of the container with lid shown in FIG. 15 in a second position;

FIG. 23 is a front view of the container and lid shown in FIG. 22;

(Continued)

FIG. 24 is a rear view of the container and lid shown in FIG. 22;
 FIG. 25 is a left side view of the container and lid shown in FIG. 22;
 FIG. 26 is a right side view of the container and lid shown in FIG. 22;
 FIG. 27 is a top view of the container and lid shown in FIG. 22; and,
 FIG. 28 is a bottom view of the container and lid shown in FIG. 22.
 The broken lines in the drawings depict portions of the container with lid that form no part of the claimed design.
